EMIL E. STOSSE, OF NEW YORK, N. Y.

COMBINED DUSTPAN AND HOLDER FOR BROOMS, ETC.

Application filed July 17, 1925. Serial No. 44,834.

This invention relates to a combined dustpan and holder for brooms and the like and has for an object to provide an improved construction over the construction shown in 5 my Patent No. 1,402,547, issued January 3, 1922.

Another object of the invention is to provide a holder which is extremely simple in construction and may be manufactured 10 cheaply.

A further object of the invention is to provide a device which may be used as a dustpan or holder for different articles, the arrangement being extremely simple where- 15 by the device may be readily grasped and manipulated for a desired purpose or may be readily hung up for receiving and supporting brooms, brushes and the like.

In the accompanying drawing—

20 Figure 1 is a sectional view through Figure 2, approximately on line 1—1, the same being on an enlarged scale, the device being shown hanging against a wall or other support.

25 Figure 2 is a plan view of the device embodying the invention, several articles being shown in dotted lines in connection therewith.

Figure 3 is an inverted perspective view 30 on a reduced scale of the device shown in Figure 2.

Referring to the accompanying drawing by numerals, 1 indicates a wall or other support adapted to be supplied with a nail, 35 pin or other device 2 which is preferably provided with an enlarged end or head. The combined pan and holder 3 is formed with an opening 4, which if desired, may be provided with a reduced slot 5 so that when 40 the device is being hung up the head of the support 2 may readily pass through the opening 4 and then the device moved downwardly so as to engage the support 2 at the end of slot 5. This will prevent accidental 45 removal.

In constructing the pan or holder 3, the same is formed very simple and preferably is a stamping pressed from sheet metal so as to be provided with a bottom 6, side walls 50 7 and 8 and an end wall 9. The side walls 7 and 8 are rounded and tapered as shown

in Figure 1 so as to provide a desired amount of side wall without presenting an undesirable amount of metal. In forming the end wall 9, the same is provided with a 55 notch 10 of a width ample to receive the handle 11 of the broom 12. This will permit a person to readily support a broom on the pan whereby it acts as a broom holder or support. In addition, other articles may be 60 supported by the device through the action of the eye members 13 and 14, which eye members are provided with threaded extensions projecting through the wall 9 and receiving the respective nuts 15 and 16. As 65 indicated in Figure 2, a dust brush 17 may be mounted on one of the eye members in any suitable manner, as for instance, by the hook 18. Likewise another form of brush or other article 19 may be mounted 70 on the eye 14 through the usual hook or other connection 20.

When the device is to be used as a dustpan, the brushes 17 and 19 and the broom 12 are all removed so that the thumb of the 75 hand may be passed through the aperture 10 and some or all of the fingers fitted into the depression 21 whereby the portion 22 of the device will act as a handle. A broom and a pair of brushes have been shown and 80 described as being supported by the device but it will be evident that other articles may be supported instead of these members if so desired.

What I claim is:

85 A dustpan, comprising a bottom, an end and sides all formed from a single piece of sheet metal, said bottom being formed at one end with an aperture for receiving a supporting member and at the opposite end with a pressed portion forming a recess, 90 said pressed portion being positioned so that one of the walls thereof co-acting with the lower part of said end presents a finger grip, said end being formed with a centrally positioned notch co-acting with said finger grip 95 whereby a thumb of a person may be passed through the notch in said end while the fingers are in said recess and thereby the pan may be readily grasped and held in any 100 desired position.

EMIL E. STOSSE.
